UNITED STATES PATENT OFFICE.

ERNST J. BOYD, ALONZO BOYD, AND THEODORE M. SLIFE, OF ARAPAHOE, NEBRASKA.

SAFETY-STIRRUP.

1,111,731.

Specification of Letters Patent.

Patented Sept. 29, 1914.

Application filed April 14, 1914. Serial No. 831,789.

To all whom it may concern:

Be it known that we, ERNST J. BOYD, ALONZO BOYD, and THEODORE M. SLIFE, citizens of the United States, residing at Arapahoe, in the county of Furnas, State of Nebraska, have invented certain new and useful Improvements in Safety-Stirrups; and we do hereby declare the following to be a full, clear, and exact description of the invention, such as will enable others skilled in the art to which it appertains to make and use the same.

This invention relates to improvements in stirrups and particularly to safety stirrups.

One object of the invention is to provide a simple device of this character which is simple in construction and is effective as well as quick in action to release the foot of the rider should he be thrown from the horse.

Another object is to provide such a structure that the same will be positive in its action and be relieved of danger of the parts catching.

Other objects and advantages will be apparent from the following description, when taken in connection with the accompanying drawings.

In the drawings: Figure 1 is an elevation of the stirrup in closed position. Fig. 2 is a similar view showing the same in inoperative position. Fig. 3 is a vertical longitudinal sectional view of the device in the position of Fig. 1. Fig. 4 is a vertical section on the line 4—4 of Fig. 1.

Referring particularly to the accompanying drawings, 10 represents the L-shaped plate which forms the main part of the stirrup, and secured to the upper end of the vertical portion is an outwardly extending pin or bolt 11. This bolt is adapted to pass through the loop 12 of the stirrup strap and has a guard loop 13 to hold the strap against sliding off. The bolt or shaft 11 has a reduced squared end 14 which passes through the square opening 15 in the upper end of the plate 16 which forms the other side of the stirrup. The outer end of the horizontal portion of the member 10 is bifurcated and has the ends of the bifurcations rolled to form the eyes 17. The lower end of the plate 16 has a reduced portion 18 which extends horizontally within the bifurcation, and secured to the plate 16 at a point where the member 18 enters the bifurcation is a bearing eye 19. This bearing eye is ar-

ranged in registration with the eyes 17 and receives therethrough a pivot pin 20. Encircling this pin between the eyes 17 and 19, and on each side of the eye 19 are the coils 21 of a spring which has one portion bent 60 upwardly as at 22 and engages with the lower portion of the plate 16. The ends of the spring at the other side of the pivot engage with the under face of the horizontal portion of the member 10 on each side of the 65 bifurcations therefor. A member 23 is disposed transversely under the bifurcation and has its ends secured to the ends of the spring, the terminals of these ends of the spring being bent laterally as indicated at 70 24. This member 23 holds the ends of the spring from slipping into the bifurcation and preventing the free operation of the device.

The free end of the member 18 is turned 75 up slightly and rests on the inner end wall of the bifurcation, and forms, together with the legs of the bifurcation, the tread plate of the stirrup. The foot of the rider rests on this tread plate, and should he be thrown 80 from the horse, the foot would pull the member 16 outwardly on its pivot, and permit the foot to readily slide out between the upper end of the plate 16 and the adjacent end of the shaft 11.

What is claimed is:

A safety stirrup comprising an L-shaped member having a horizontal portion bifurcated, a second L-shaped member having a horizontal portion reduced and movable 90 within the bifurcation, said second L-shaped member being pivotally connected to the outer end of the bifurcated portion of the first member, a spring mounted on the pivot of the members, one end of the spring bearing 95 on the second member, the spring at the opposite side of the pivot having the ends engaging under the portions of the bifurcations, and a transverse member secured to the said spring ends for holding said spring 100 ends from engaging in the bifurcation.

In testimony whereof, we affix our signatures in the presence of two witnesses.

ERNST J. BOYD.
ALONZO BOYD.
THEODORE M. SLIFE.
